MECHANISM FOR WEIGHING AND DISCHARGING ARTICLES INTO SELECTED COMPARTMENTS

Donald B. Tolley, Macomb, Ill., assignor to Globe American Corporation, Kokomo, Ind., a corporation

Application March 31, 1944, Serial No. 528,881

5 Claims. (Cl. 209—121)

1

This invention relates to an apparatus for automatically grading articles, such as eggs, according to weight, being also applicable to other articles wherein it is desired to selectively group them relative to each other within predetermined weights.

The invention contemplates a machine of the endless carrier or rotary type having a series of lever balances with a counterweighted tray mounted on each end for carrying the article to be graded, and in association with a series of bins into which the articles are selectively ejected from the tray, dependent upon the extent to which the weight of the article depresses the balance.

The object of this invention is to simplify and render more positive the action of the directing element and ejector for directing the trays to the position for either ejecting or not ejecting the article into an associated bin wherein the weight of the article lies in a "twilight" zone.

Another feature of the invention resides in combining the function of the directing element and ejector to serve both the purpose of directing the scale when the weight is in the "twilight" zone and ejecting the article therefrom into its proper bin when of a predetermined weight.

Another feature of the invention resides in mounting a roller in association with each bin, adapted to serve as the directing element and ejector, and for engagement by the article supporting tray upon the scale, or a selecting finger associated therewith, such that the tray or fingers will be caused to roll under or over the directing element or the ejector to prevent such abutting engagement as to jam the machine.

The full nature of the invention will be understood from the accompanying drawings and the following description and claims:

Fig. 1 is a plan view of the grader. Fig. 2 is a section taken on the line 2—2 of Fig. 1, showing a portion thereof in elevation. Fig. 3 is an elevation of one of the scales showing it being guided under one of the directing elements. Fig. 4 is the same as Fig. 3, showing it being directed thereover. Fig. 5 is a schematic view of the different relative heights of the bins and directing elements progressing from left to right of Fig. 1.

In the drawings there is shown a grader having a supporting base 10 about which are mounted a plurality of bins 11 extending radially about a turntable 12. Each of said bins is adapted to receive those articles, such as eggs indicated at 13, of the prescribed weight within certain predetermined limits. Beginning at the left-hand side of Fig. 1, the first bin is adapted to receive articles of the heaviest weight. The next bin receives those articles coming within the next weight group, and etc. on to the last bin which receives the articles coming within the lightest

2

permissible weight. Those articles that are too light for grading may be carried on for discharge in any desired manner or the ejector in the last bin may be arranged to remove articles too light to have been previously ejected.

The turntable 12 is rotatably supported upon the base 10 by a bearing 14 being rotated by a driven belt 15 and pulleys 16 from a reduction motor indicated at 17. Mounted at regular intervals about the periphery of the turntable there are supporting brackets 18 each of which supports a radially directed balance scale comprising a beam 19 and compensating lever 20. Each scale is provided with an article receiving tray 21 on the outer end thereof and a compensating weight 22 on the inner end. By reason of the parallelogram action between the lever 20 and beam 19 the trays are always maintained in horizontal position irrespective of the movement of the scale. Centrally mounted on the turntable there is provided a rubber faced bumper 23 engageable by the inner ends of the scales. When the scales are free, the counterbalance weights 22 are so adjusted that the article will depress the tray to a predetermined level within a prescribed range. However, at the loading station, opposite the bins 11, there is a wire supporting frame 24 upon which the scale rides.

The bins 11 are separated by partitions 25 and at or adjacent each of said partitions there is mounted a directing element or roller 26. Said roller is supported to freely rotate between the ears 27 on a supporting bracket 28, said supporting bracket extending through the bottom of the bin and carried by a standard 29 which is secured to the base 10.

Each of the trays 21 is provided on its leading side with a selecting finger 30 which preferably has a sharp pointed end for engagement and 40 rolling contact with the directing roller 26, as indicated in Figs. 3 and 4. This arrangement is such that if the weight of the article depresses the tray into a "twilight" zone with respect to one of the directing rollers, the pointed end of the 45 selecting finger will engage such roller. But by reason of the pointed end thereof and the cylindrical surface of the roller, said finger will be caused to either roll under or over the roller and not become wedged thereagainst. Thus, the tray 21 is caused to be guided by the finger, either under or over the roller. It is to be understood, however, that wherein the weight of the article is not such as to depress the tray in the "twilight" 50 zone, it, together with its finger, may either pass under the roller free of contact therewith, or over the roller. In this manner, as the tray progresses, and by reason of the stepped up position of the rollers at different relative heights, if it passes over the first roller, it may pass under the second or one of the subsequent rollers. As

the tray passes under one of the rollers 26, such roller acts as an ejector for engaging and ejecting the article from the tray into the bin with which said ejector roller is associated. In this action, by reason of the curved rolling surface and the angular disposition of the ejecting roller relative to the path of travel of the article, the ejecting action will be given a sliding glancing impact such as to minimize injury to the article. It may likewise be noted that by reason of the rolling cylindrical surface of the directing roller and ejector, the danger of injury to an operator caught between the progressing tray and roller will be eliminated.

By reason of the varying relative heights of the ejectors, the tray with its article will be caused to pass under one or the other and the article thereby ejected into the bin associated with the particular ejector under which the tray passes, depending upon the extent that the scale is depressed by the weight of the article. Whereas in its simplified form the finger 30 is shown as mounted directly upon the leading side of the tray, or formed integral therewith, it is obvious that the finger may be otherwise associated with the tray. Likewise, whereas for simplification the roller 26 serves both as a directing element and an ejector, it may serve only as one or the other. Thus, it may serve as a directing element, as above described, whereas an additional element may be associated with the bin at the proper position to engage and eject the article from the tray passing thereunder. Similarly, whereas the roller is shown in its most simple arrangement as being mounted upon the bin, it obviously may be otherwise mounted in association with the bin.

Wherein the term "bin" is used herein to designate the receptacles into which the graded articles are discharged, it is to be understood that said term is employed in its broadest sense to include bags, chutes, conveyors or the like.

The invention claimed is:

1. A weight grader including a plurality of sorting bins for receiving articles graded according to their relative weights, a plurality of scales, each of said scales being provided with an article supporting tray, means for supporting said scales to be progressively movable over said bins, a directing roller pivotally mounted adjacent each bin, said rollers extending in progressively stepped planes, a selecting member associated with each scale movable therewith in a path through said rollers, and a cam portion on the upper and lower edge of said member engageable with one of said rollers depending upon the position of its scale for camming said member and scale under or over such engaged roller, whereby said roller will be caused to engage and eject the article from its tray into its associated bin.

2. A weight grader including a plurality of sorting bins for receiving articles graded according to their relative weights, a plurality of scales, each of said scales being provided with an article supporting tray, means for supporting said scales to be progressively movable over said bins, a directing roller pivotally mounted adjacent each bin, said rollers extending in progressively stepped planes, a selecting finger formed to project from the leading edge of each of said trays movable therewith in a path through said elements, and a tapered cam surface formed on said finger for camming said tray over or below an engaged roller, whereby an article carried by the

tray directed under said roller will be ejected thereby into the associated bin.

3. A weight grader including a plurality of sorting bins for receiving articles according to their relative weights, a plurality of radially-extending balance scales pivotally supported intermediate their ends, a counterbalanced tray on the outer end of each scale for receiving one of said articles, a rotatable support for said scales movable to direct said trays progressively over said bins, a series of directing and ejecting rollers rotatably supported in association with said bins at different relative heights thereover, one of said rollers being associated with each bin, and means on each tray depressible by the weight of the article and engageable with one of said rollers to direct said tray thereby, said roller acting to eject the article from said tray upon directing said tray thereunder while permitting said article to remain upon said tray when said tray is directed thereover.

4. A weight grader including a plurality of sorting bins for receiving articles according to their relative weights, a plurality of radially-extending balance scales pivotally supported intermediate their ends, a counterbalanced tray on the outer end of each scale for receiving one of said articles, a rotatable support for said scales movable to direct said trays progressively over said bins, a series of directing and ejecting rollers rotatably supported on said bins at different relative heights thereover, one of said rollers being associated with each bin, and a selecting finger having tapered cam surfaces thereon forwardly of the leading edge of each tray, said finger being depressible by the weight of the article carried in said tray for engagement with one of said rollers to direct said tray thereunder when in one position and direct said tray thereover when in another position, said roller acting to engage and eject the article from said tray upon said tray being directed thereunder by said finger.

5. A weight grader including a plurality of sorting bins for receiving articles graded according to their relative weights, a plurality of scales, each of said scales being provided with an article supporting tray, means for supporting said scales and bins for movement relative to each other with the scales above said bins, a directing roller pivotally mounted adjacent each bin, said rollers extending in progressively stepped planes, and a selecting member associated with each scale positioned for engagement by one of said rollers depending upon the article carrying position of the scale, said selecting members being operative to elevate their respective trays to bypass one of said rollers upon engagement therewith, or depress its respective tray for causing the article carried thereby to be ejected into the associated bin by the engaged roller.
